(57) **CLAIM**

The ornamental design for a multimedia work table for multiple personal computers, as shown and described.

DESCRIPTION

FIG. 1 is a perspective illustration of the multimedia work table for multiple personal computers showing our new design:

FIG. 2 is a perspective illustration thereof taken from a lower elevation and with the worktable partly rotated;

FIG. 3 is a front elevational view thereof;

FIG. 4 is an enlarged front elevational view thereof partially rotated; and,

FIG. 5 is a plan view thereof.
